UNITED STATES PATENT OFFICE.

JAMES G. CARY, OF JACKSON, TENNESSEE.

REGISTER.

1,073,957.

Specification of Letters Patent. Patented Sept. 23, 1913.

Application filed August 13, 1912. Serial No. 714,831.

To all whom it may concern:

Be it known that I, JAMES G. CARY, a citizen of the United States, residing at Jackson, in the county of Madison and 5 State of Tennessee, have invented new and useful Improvements in Registers, of which the following is a specification.

This invention is a register for numbered ice coupon books, drafts, checks, and the 10 like, by means of which the coupons, drafts, checks, or the like, of any number may be instantly found on the register to facilitate the making of an entry or entries with respect thereto, my improved register comprising 15 a series of consecutively numbered leaves, the opposed edges of two adjacent leaves, when the book is in open position, comprising a pair of sections, each page of a pair of sections being ruled to provide 20 alined main spaces extending across the sections, said spaces being further ruled transversely to provide five sub spaces in each main space, the main spaces being numbered progressively from "0 to 9" and the sub 25 spaces being consecutively numbered from "1 to 100", all of the odd numbers being on one section and the even numbers on the other, and the lowest number of the main and sub spaces beginning at the same edge 30 of the book, as hereinafter more fully described and claimed.

In the accompanying drawings:—Figure 1 is a plan of a register constructed in accordance with my invention and open at the 35 first page. Fig. 2 is a similar view of the same, open at the third page, or page numbered "3", and representing three hundred. Fig. 3 is a detail perspective view, showing a portion of a register designated 40 as a V-register. Fig. 4 is a similar view, showing a portion of a register designated as an X-register. Fig. 5 is a perspective view of a coupon book such as adapted for 45 use in connection with my improved register.

My improved register is a blank book of suitable size and shape and is here shown as comprising a series of consecutively numbered leaves *a*, the opposite pages of two 50 adjacent leaves, when the book is in open position, comprising a pair of sections *b*—*c*. Each page of a pair of sections is ruled to provide alined main spaces extending across the sections and the said main spaces are 55 further ruled transversely with common horizontal lines *d* to provide five stub spaces

in each main space. The main spaces are numbered progressively from "0 to 9", said designating numbers being arranged in a column *m* between the sections. The sub 60 spaces of each section are consecutively numbered from "1 to 100", all the odd numbers being on one section and the even numbers on the other. The lowest numbers of the main and sub spaces begin at the 65 same edge of the book. The numbers of the sub spaces are arranged in columns *e*. The sections are also shown as ruled to form date columns *f*, name columns *g*, street or number columns *h*, due columns *i*, paid columns 70 *k* and "Sold by" columns *l*. These columns may be appropriately designated and adapted for containing entries or data of any required nature and I would have it understood that I am not limited in this respect. 75

The first page is numbered "0" and is for numbered coupons, drafts, checks and the like, running from 1 to 100 each of the other pages being numbered 1, 2, 3, or the like, to indicate corresponding hundreds. 80

To locate any desired number, it is only necessary to turn to the page corresponding with the hundreds value of said number and then refer to its units or tens value in the column *e*, the group numbers *m* greatly facilitating this reference so that with a very little practice any number may be instantly found, and even without the conscious operation of the mind. 85

The pages, in addition to being numbered 90 to indicate hundred consecutively, are also preferably provided with corresponding index numbers *p*, the edges being cut away as required to expose said index numbers.

In practice, I propose to make my register in two sizes, a small size indexed from "0" to "49" pages with a registering capacity of five thousand consecutive numbers, and a larger size indexed from "0" to "99" pages with a registering capacity 100 of ten thousand consecutive numbers. A register of five thousand capacity will be designated a "V" register as indicated in Fig. 3 and one of ten thousand capacity an "X" register as indicated in Fig. 4. When 105 coupon books or articles of any kind are sold which require registering and to a number in excess of the capacity of either register, the serial letter A, which, in effect is the same as the unit 1, will be printed 110 to the right of every consecutive number on such coupon books, and a V or an X will be

printed to the left of or before each consecutive number on such coupon books. A would indicate that all the numbers which it follows are recorded in the first register, 5 and V or X would indicate whether the register is of five thousand capacity or ten thousand capacity, as the case may be. A second issue of such coupon books would be lettered B and a third issue would be lettered C and 10 so on throughout the alphabet, the added letter indicating the designating value of the issue and of the register in which it is recorded, and the prefixed letter V or X indicating whether that issue is recorded in a register 15 of five thousand capacity or one of ten thousand capacity, as the case may be.

To estimate: If an order is given for ten thousand ice coupon books numbered from one to ten thousand, consecutively, X would 20 be printed before each and every consecutive number on such books and A after each of such numbers. If a second like order is given, X would be printed before each and every consecutive number on such books 25 and B after each of such numbers. If a third like order is given, X would be printed before each and every consecutive number on such books and C after each of such numbers, and so on. Thus, a ticket from 30 one of such books designated X 10,000 C as shown in Fig. 5 would indicate that such book would be the last number found in a register of ten thousand capacity, and as it was marked with a C following the number, 35 it would indicate that three of such regis-

ters had been filled, and, hence, thirty thousand such books had been sold and recorded. In other words, the ticket would indicate such facts and make it unnecessary to refer to the register to see. Should ice ticket books numbered from one to five thousand be ordered, V would be printed before each number, to indicate that all the numbers it preceded would be found in a V register of five thousand capacity. 40 45

I claim:—

The herein described register for numbered coupons, checks, drafts and the like comprising a series of consecutively numbered leaves, the opposed pages of two adjacent leaves, when the book is in open position, comprising a pair of sections, each page of a pair of sections being ruled to provide alined main spaces extending across the sections, said spaces being further ruled transversely to provide five sub spaces in each main space, the main spaces being numbered progressively from "0 to 9" and the sub spaces of each section being consecutively numbered from "1 to 100", all the odd numbers being on one section and the even numbers on the other and the lowest number of the main and sub spaces beginning at the same edge of the book. 50 55 60

In testimony whereof I affix my signature 65 in presence of two witnesses.

JAMES G. CARY.
